DESIGN FOR A CASE FOR CLOCKS OR SIMILAR ARTICLES

Frederick E. Greene, Westport, Conn., assignor
to The Sessions Clock Company, Forestville,
Conn., a corporation of Connecticut

Application November 24, 1939, Serial No. 88,449

Term of patent 14 years

To all whom it may concern:

Be it known that I, Frederick E. Greene, a citizen of the United States, residing at Westport, in the county of Fairfield and State of Connecticut, have invented a new, original, and ornamental Design for a Case for Clocks or Similar Articles, of which the following is a specification, reference being had to the accompanying drawing, forming part thereof.

Fig. 1 is a face view of a clock case showing my new design; and

Fig. 2 is a view thereof in edge elevation. The characteristic feature of my new design resides in the case exaggeratedly simulating the figure of a chef and mounting a clock or similar article in the abdominal portion of the figure.

I claim:

The ornamental design for a case for clocks or similar articles, substantially as shown and described.

FREDERICK E. GREENE.
